UNITED STATES PATENT OFFICE

SAMUEL M. LANGSTON, OF WENONAH, AND WILLIAM H. CLEAVER, OF AUDUBON, NEW JERSEY, ASSIGNORS TO SAMUEL M. LANGSTON CO., OF CAMDEN, NEW JERSEY, A CORPORATION OF NEW JERSEY

SLOTTING AND SCORING MECHANISM

Application filed November 11, 1930. Serial No. 494,842.

The present invention relates to a new and improved mechanism for slotting and scoring sheet material in the making of box blanks.

In a machine of this general type, it has been customary to provide a series of pairs of co-acting rotary members between which the sheet is advanced to score it along a series of fold lines, and a second series of pairs of co-acting rotary members, between which the sheet is advanced to slot it at one or both ends of each of the score or crease lines to separate adjacent portions which may be later folded to form the ends or end flaps of the box. A machine of this general type is disclosed in the Langston Patent 1,769,883, dated July 1, 1930.

In said patent, there is provided interengaging parts between the scoring and slotting mechanisms, so that unisonal axial movement thereof is effected, and so that the position of each slot will bear a fixed relationship to the position of its associated crease line in the sheet. Sometimes, however, it is desirable to change the relative position of each slot with respect to the position of its related crease line in the sheet. For instance, when the slots are positioned in exact center line registry with their related score lines, the edges of the outside flaps will project flush with or possibly slightly beyond the side surface of the resultant box when folded into shape. Thus in shipment or handling, the edges of the flap is often caught and pulled up to loosen the flap or give the box the appearance of being damaged.

The present invention provides a mechanism for easily and quickly effecting independent axial movement of the scoring and slotting mechanism, whereby the position of the slot can be selectively adjusted with respect to the position of its related crease or score line in the sheet.

The present invention still further provides easily accessible adjusting members for effecting the independent axial movement of the scoring and slotting mechanisms.

The invention also includes certain other new and important features of construction

and combinations of parts hereinafter set forth and claimed.

Although the novel features which are believed to be characteristic of this invention will be particularly pointed out in the appended claims, the invention itself, as to its objects and advantages, the mode of its operation and the manner of its organization may be better understood by referring to the following description of one specific form taken in connection with the accompanying drawings forming a part thereof, in which

Fig. 1 is a vertical section through a portion of a machine embodying the invention and showing one set of the scoring and slotting units.

Fig. 2 is a front elevation showing the slotting mechanism with its associated adjusting means.

Fig. 3 is a front elevation showing the scoring wheel and its associated adjusting means.

Fig. 4 is a section taken on line 4—4 of Fig. 1.

Fig. 5 shows a plan view of a box blank having slots in exact center line registry with their related score lines.

Fig. 6 is a perspective of part of a box formed from the blank shown in Fig. 5.

Fig. 7 is a plan view of a box blank in which the slots are disposed out of exact center line registry with their related score lines, and

Fig. 8 is a perspective of a portion of the box formed from the blank shown in Fig. 7.

Like reference characters denote like parts in the several figures of the drawings.

In the following description and in the claims parts will be identified by specific names for convenience, but they are intended to be as generic in their application to similar parts as the art will permit.

The machine of the present invention can be adjusted to form a box blank of the type shown in Fig. 5 in which the blank is provided with slots 10 disposed in exact center line registry with their related score lines 11, and extending from transverse score lines 12. Such a blank forms a box as shown in Fig. 6 having the edges of the outside flaps flush

with or projecting beyond the side contour of said box.

The machine can be equally adapted to form the box blank shown in Fig. 7 with slots 10a disposed in offset relationship with respect to their associated score lines 11a. A box constructed from a blank of this type will form a box shown in Fig. 8 with the sides of the outside flaps well within the side contour of said box.

10 For scoring or creasing the blank to form the score lines 11 or 11a, any suitable scoring mechanism known in the art may be employed. One form of mechanism which may be used for that purpose includes a plain surfaced roller 13, splined to a shaft 14 and having cooperating therewith a scoring wheel 15. This wheel 15 has a scoring periphery 16 of V or other appropriate form and is splined to a shaft 17 for rotation therewith and axial movement therewith. A number of these scoring units are positioned along their respective shafts and the distance between successive units determined in accordance with the desired size and proportions of the box 25 to be formed.

The slotting mechanism may be of the usual well-known construction, and in the form shown in the drawings includes an upper slotting head 20, splined to a shaft 21, and having mounted thereon a pair of blades 22 for making the side cuts of the slot and a nib part 23 for making the end cuts. These blades 22 are relatively adjustable circumferentially so 30 as to effect any selective length of the box between the score lines 12. A lower slotting head 24 has a groove 25 for the engagement of said blades and is splined to a shaft 26 for axial movement therewith. All four shafts 14, 17, 21 and 26 are rotated in synchronism by 35 any suitable means such as that shown in the prior Langston patent above referred to.

In order to move the scoring wheel 15 axially, there is provided a fixed bar 30, having 40 connected thereto a rack 31, which meshes with a pinion 32. This pinion 32 is journaled between two slider members 33 and 34 which embrace the bar 30 and which are connected together to travel along said bar. One end of 45 the shaft of the pinion 32 has secured thereto a collar 35 and the other end projects beyond the slider member 34 and forms a head 36 which is shaped for the reception of a suitable turning tool.

50 Connected to the slider member 34 and abutting the sides of the lower scoring member are plates 37. These plates are advantageously provided with linings 38 of suitable material for obviating metallic clashing between said plates and the scoring member. By means of this arrangement, when it is desired to axially move the scoring wheel 15, the pinion 32 is turned in response to the manipulation of the head 36 so that the sliders 55 33 and 34 are moved along the bar 30. This

movement of the sliders effects the movement of the plates 37 and the corresponding movement of the scoring wheel 15 along its shaft 17.

In order to clamp the slider members in 70 a fixed position after the desired adjustment has been effected, a screw member 39 is provided passing through both sliders 33 and 34 and having a head 39 which is shaped to receive the same turning tool as that used for 75 the pinion.

In order to effect the axial adjustment of the slotting heads 20 and 24, a fixed bar 40 is provided. Embracing said bar 40 are slider members 41, 42 and 43 connected together so 80 as to move in unison. Fixed to the bar 40 is a rack 44 which engages a pinion 45 loosely mounted on the slider 41. This pinion 45 has its shaft extending beyond said slider in substantially parallel relationship with the shaft 85 of the pinion 32 and terminating in a head 46 shaped to receive the said turning tool.

Connected to the sliders of the slotting mechanism and engaging both sides of the header 24 are plates 47 having a lining 48 90 similar to the lining 38. By turning the pinion, the whole slider mechanism will be axially displaced, and the slotting head 24 will be carried therewith by the engagement of the plates 47. If the upper slotting head be 95 stopped with its blade in the groove of the lower head, both heads will be moved simultaneously.

We provide means for indicating from the setting of machine the amount of offset between the score lines and the slots. This includes a pointer connected for movement on either the scoring or slotting mechanism and registration marks operating with said pointer and positioned for movement with the other mechanism. In the specific form of this means shown, the front face of the slider 100 41 is provided with a calibration 50. Indicatively cooperating with said calibration is a pointer 51 offset from one end of a shank 105 52 which is threaded or otherwise connected to the slider member 34. This pointer 51 has a mark which registers with the calibration 50. When it is desired to construct a blank as shown in Fig. 5, the mark on the pointer 110 51 is made to register with the zero mark on the calibration 50. When it is desired to displace the slots in any selective position with respect to their related creases, the slotting mechanism is moved the desired distance 115 from either side of the zero mark as indicated by the pointer 51.

It should be noted that the two adjusting heads 36 and 46 and the clamping head 39 extend in substantially parallel relationship 120 and are sufficiently close together to permit the manipulation thereof by one person without substantially shifting his position.

In the operation of the machine, the adjusting head 36 is turned to axially move the 130

scoring wheel 15 along its shaft 16 in accordance with the desired shape of the box to be formed. This scoring wheel 15 is then clamped in position against axial movement by means of the screw member and the slotting head 24 axially moved as already described to effect the desired alinement or offset between the crease line and its associated slot.

Having thus described our invention, what we claim as new and desire to secure by Letters Patent is:

1. A slotting and scoring mechanism including a rotary slotting head, a scoring wheel cooperating with said slotting head for substantial aligned operation, a pair of rotatable adjusting members, means responsive to the rotation of one of said members for axially moving said slotting head independently of said scoring wheel, and means responsive to the rotation of the other of said adjusting members for moving said scoring wheel independently of said slotting head, said adjusting members being at different elevations and beneath said wheel and head, and sufficiently close together so that the manipulation thereof can be effected without substantial change in the position of the manipulator, either of said members being movable past the other axially of said wheel and head.

2. A machine for making box blanks including a rotary head for slotting the blank, a wheel for scoring said blank in substantial alinement with the slot formed by said slotting head, a pair of fixed bars extending substantially parallel to the axes of said head and wheel, separate racks secured to said bars, a pair of members separately slideable along said bars and engaging said slotting head and said wheel respectively, pinions loosely mounted on said members and meshing with said racks, the shafts of said pinions extending beyond said members whereby said pinions may be turned, said pinions being disposed with their axes in substantially parallel relationship and sufficiently close together so that they may be rotatively manipulated without any necessity for the manipulator changing his position.

3. A machine for making box blanks including a rotary member for slotting the blank, a rotary member for scoring said blank in substantial alinement with the slot formed by said slotting member, a mechanism for axially moving one of said members with respect to the other, and means including a pointer movable with one of said members for indicating the relative axial position of said members.

4. A slotting and scoring mechanism including a rotary head for slotting a blank, a wheel for scoring said blank in substantial alinement with the slot formed by said slotting head, a pair of bars, a pair of slider

members adapted for independent sliding movement along said bars and engaging said head and said wheel respectively, and means for indicating the relatively axial position of said slotting head and said scoring wheel, said means including a pointer secured to one of said slider members and cooperating with a mark on the other slider member.

5. A slotting and scoring mechanism including a rotary slotting head, a scoring wheel cooperating with said slotting head for substantial aligned operation, a pair of rotatable adjusting members, means responsive to the rotation of one of said members for axially moving said slotting head independently of said scoring wheel, means responsive to the rotation of the other of said adjusting members for moving said scoring wheel independently of said slotting head, a third rotatable member, and means responsive to the rotation of said third member for clamping said scoring wheel against axial movement, said three rotatable members having their axes substantially parallel and sufficiently close together so that the manipulation thereof can be effected without substantial change in the position of the manipulator.

6. A slotting and scoring mechanism including a rotary head for slotting a blank, a wheel for scoring said blank, a pair of bars, a pair of slider members adapted for independent sliding movement along said bars and engaging said head and said wheel respectively, means for indicating the relatively axial position of said slotting head and said scoring wheel, said means including a pointer secured to one of said slider members and cooperating with a mark on the other slider member, and clamping means for locking one of said slider members against sliding movement.

7. A slotting and scoring mechanism including a rotary slotting head, a scoring wheel for substantially aligned operation therewith, a pair of fixed rack bars mounted at different elevations, and extending in directions substantially parallel to the axes of said head and wheel, a pair of separate members slideable along said rack bars and engaging said head and said wheel respectively, pinions loosely mounted on said members, meshing with the racks, and having shafts extending on the same side of the mechanism and at right angles to the axes of the slotting head and scoring wheel, said shafts being disposed at different elevations and below said head and wheel, with the shaft of the pinion engaging the lower rack bar extending beneath the upper rack bar, each of said shafts and its pinion being movable past the other in a direction parallel to the axes of said head and wheel.

8. A slotting and scoring mechanism including a rotary slotting head, a scoring wheel for substantially aligned operation

therewith, a pair of fixed bars located below said slotting head and scoring wheel, horizontally interspaced, and extending in directions substantially parallel to the axes of
5 said slotting head and scoring wheel, separate racks secured to said bars, one of said racks being secured to a side face of one of said bars, the other rack being secured to the bottom edge of the other bar, a pair of separate members slidable along said bars and engaging said head and wheel respectively, pinions loosely mounted on said members, meshing with said racks, and having shafts extending on the same side of the mechanism
10 and at right angles to the axes of the slotting head and scoring wheel, said shafts being disposed at different elevations and of such lengths that each of said shafts and its pinion may be moved past the other in a direction
15 parallel to the axes of said head and wheel.

Signed at Camden in the county of Camden and State of New Jersey this 8th day of November, 1930.

SAMUEL M. LANGSTON.
WILLIAM H. CLEAVER.
